Atty.

UNITED STATES PATENT OFFICE.

JAMES WILLIAM DECKERT, OF OAKVILLE, CANADA.

PNEUMATIC HAIR-COLLECTOR.

No. 825,961.

Specification of Letters Patent.

Patented July 17, 1906.

Application filed October 4, 1905. Serial No. 281,260.

To all whom it may concern:

Be it known that I, JAMES WILLIAM DECKERT, a citizen of the United States of America, residing in the town of Oakville, in the county of Halton, in the Province of Ontario, Canada, have invented certain new and useful Improvements in Pneumatic Hair-Collectors, of which the following is a specification.

- 10 My invention relates to improvements in pneumatic hair-collectors; and the object of my invention is to design an apparatus that will convey away the cut hair, thus preventing it from falling on the individual and thence to the floor. Particularly in warm weather is it well known that when one is having a hair-cut the perspiration causes the cut hairs to adhere to the individual's neck (notwithstanding the precautions that are 15 taken to prevent this) and gradually work down.
- 20 My invention is, broadly, a pneumatic hair-collector provided with a channel, conduit, or passage-way through or in which the hair is drawn by an air-current.

Figure 1 is a general perspective view of one form of my invention. Fig. 2 is an enlarged vertical cross-section on the line *a b*, Fig. 1; and Fig. 3 is a detail view hereinafter referred to.

In the drawings like characters of reference indicate corresponding parts in each figure.

I shall now describe one species of my invention.

35 A is the body or main portion, and the same is suitably constructed so as to be detachably secured to the person having a hair-cut. As shown, the body or main portion A is formed of a brim or ledge which surrounds or incloses an opening or space A' and extends out from the head so as to intercept the cut hair.

40 In order to enable the apparatus to perform the function of conveying away the cut hair, the body or main portion A is provided with a channel, conduit, or passage-way B, having any suitable discharge-opening or discharge-conduit C. By any suitable means, 45 such as an electric fan, (not shown,) connected to the conduit, channel, or passage-way B by the pipe or tube D a strong current of air is drawn through said conduit, channel, or passage-way B, thus conveying the cut hair 50 away.

Upon referring to Fig. 2 it will be seen that

the body or main portion A is preferably dish-shaped in cross-section and that the conduit, channel, or passage-way B is formed at the lowermost part of the dish-shaped configuration, so as to facilitate the passage of the hair thereinto.

If desired, I may construct a number of branch conduits, channels, or passage-ways E in the body or main portion A and which communicate with the conduit, channel, or passage-way B, so as to facilitate the conveying away of the hair. The species of my invention shown is provided with an upwardly-extending flange F, which surrounds or 60 incloses the space or opening A' and by means of which it is held in position on the individual.

If desired, I may suitably line the flange F with a strip of suitable material G, which may be made so as to normally exert the desired pressure against the head, so as to retain the apparatus in position.

If desired, the apparatus may be made adjustable, so as to fit different-sized heads. 65 According to the construction shown for this purpose the body or main portion A is divided at its upper end and the adjacent ends are overlapped, as shown. This division of the main or body portion A necessitates the 70 division of the flange F and the strip G, one of which overlaps the other at their adjacent ends, as shown. By any suitable means, such as a buckle H and a strap I, coöperating therewith, the apparatus can be adjusted to 75 fit different-sized heads.

It is immaterial what my apparatus may be made of. It may be either made of rubber, celluloid, aluminium, or any other suitable material.

80 When my invention is designed to be used on the head, it will be constructed so as to occupy approximately the position shown in Fig. 1. This figure shows a dotted head and my apparatus placed so as to be well below what I might term the "hair-line," thus 85 absolutely preventing any interference with the barber as he cuts the hair.

85 It will be noted that by means of my invention the unsightly collection of hair on the floor of a barber-shop will be absolutely prevented, thus keeping these shops clean and neat. Furthermore, by means of my invention a barber will be enabled to dispense with the usual boy employed to sweep the hair up.

90 I do not confine myself to the construction shown and described, as I lay broad claim to

any apparatus that will perform the same function as mine after the same manner.

What I claim as my invention is—

1. A pneumatic hair-collector provided with a channel, conduit, or passage-way through which the hair is drawn by an air-current.
2. A pneumatic hair-collector provided with a discharge opening or conduit, and being further provided with a channel, conduit, or passage-way opening into said discharge opening or conduit.
3. A pneumatic hair-collector provided with a discharge opening or conduit, and being further provided with a channel, conduit, or passage-way communicating therewith and which is provided with a plurality of branch conduits.
4. A hair-collector comprising a dish-shaped body or main portion provided with a discharge opening or conduit, and being further provided at its lowermost part of its dish-shaped configuration with another conduit, channel, or passage-way communicating therewith and which is provided with a plurality of branch conduits.
5. A hair-collector comprising an adjustable dish-shaped body or main portion provided with a discharge opening or conduit, and being further provided at its lowermost part of its dish-shaped configuration with another conduit, channel, or passage-way communicating therewith and which is provided with a plurality of branch conduits, and means for adjusting said apparatus.
6. A hair-collector comprising a body or main portion provided with a conduit, channel, or passage-way having one or more branch conduits opening thereinto.
7. A hair-collector comprising an adjustable body or main portion provided with a conduit, channel, or passage-way having one or more branch conduits opening thereinto.
8. A hair-collector comprising a body or main portion provided with a conduit, channel, or passage-way by means of which the cut hair is conveyed away through a discharge-opening with which it is provided by an air-current passing therethrough.
9. An apparatus of the class described comprising a brim or ledge surrounding or inclosing an opening or space, and being provided with a conduit, channel, or passage-way, by means of which the hair is conveyed away by an air-current passing therethrough.
10. An apparatus of the class described comprising a brim or ledge surrounding or inclosing an opening or space, and being provided with a discharge opening or conduit, and being further provided with another conduit, channel, or passage-way opening into said discharge opening or conduit.
11. An apparatus of the class described comprising a brim or ledge surrounding or inclosing an opening or space, and being provided with a discharge opening or conduit, channel, or passage-way communicating therewith and which is provided with a plurality of branch conduits.
12. An apparatus of the class described comprising an adjustable brim or ledge surrounding or inclosing an opening or space, and being provided with a discharge opening or conduit, and being further provided with another conduit, channel, or passage-way communicating therewith and which is provided with a plurality of branch conduits, and means for adjusting said brim or ledge.
13. An apparatus of the class described comprising an adjustable brim or ledge provided on its inner edge with a flange, surrounding or inclosing an opening or space, and being provided with a discharge opening or conduit, and being further provided with another conduit, channel, or passage-way communicating therewith and which is provided with a plurality of branch conduits, and means for adjusting said brim or ledge.
14. An apparatus of the class described comprising an adjustable brim or ledge provided on its inner edge with a flange, surrounding or inclosing an opening or space, and being provided with a discharge opening or conduit, and being further provided with another conduit, channel, or passage-way communicating therewith and which is provided with a plurality of branch conduits, and a lining of suitable material for said flange.
15. An apparatus of the class described comprising an adjustable brim or ledge provided on its inner edge with a flange, surrounding or inclosing an opening or space, and being provided with a discharge opening or conduit, and being further provided with another conduit, channel, or passage-way communicating therewith and which is provided with a plurality of branch conduits, and means for adjusting said brim or ledge, and a lining for said flange being made of suitable material so as to exert the desired inward pressure.
16. An apparatus of the class described comprising a dish-shaped brim or ledge surrounding or inclosing an opening or space, and being provided at its lowermost part of its dish-shaped configuration with a conduit, channel, or passage-way by means of which the hair is conveyed away by an air-current passing therethrough.
17. An apparatus of the class described comprising a dish-shaped brim or ledge surrounding or inclosing an opening or space, and being provided with a discharge opening or conduit, and being further provided at its lowermost part of its dish-shaped configuration with a conduit, channel, or passage-way opening into said discharge opening or conduit.

18. An apparatus of the class described comprising a dish-shaped brim or ledge surrounding or inclosing an opening or space, and being provided with a discharge opening or conduit, and being further provided at its lowermost part of its dish-shaped configuration with a conduit, channel, or passage-way communicating therewith and which is provided with a plurality of branch conduits. 40
19. An apparatus of the class described comprising an adjustable dish-shaped brim or ledge surrounding or inclosing an opening or space, and being provided with a discharge opening or conduit, and being further provided at its lowermost part of its dish-shaped configuration with a conduit, channel, or passage-way communicating therewith and which is provided with a plurality of branch conduits, and means for adjusting said brim or ledge. 45
20. An apparatus of the class described comprising an adjustable brim or ledge provided on its inner edge with a flange surrounding or inclosing an opening or space, and being provided with a discharge opening or conduit, and being further provided at its lowermost part of its dish-shaped configuration with a conduit, channel, or passage-way communicating therewith and which is provided with a plurality of branch conduits; means for adjusting said brim or ledge, and a lining of suitable material for said flange. 50
21. An apparatus of the class described comprising a brim or ledge surrounding or inclosing an opening or space, and being provided with a conduit, channel, or passage-way by means of which the cut hair is conveyed away through a discharge-opening with which it is provided by an air-current passing therethrough. 55
22. An apparatus of the class described comprising a brim or ledge surrounding or inclosing an opening or space and being provided with a conduit, channel, or passage-way having one or more branch conduits. 60
23. An apparatus of the class described comprising an adjustable brim or ledge provided on its inner edge with a flange made of suitable material so as to exert the desired inward pressure, and surrounding or inclosing an opening or space, and being provided with a discharge opening or conduit, and being further provided with another conduit, channel, or passage-way communicating therewith and which is provided with a plurality of branch conduits. 65
24. An apparatus of the class described comprising a brim or ledge provided on its inner edge with a flange made of suitable material so that it will exert the desired inward pressure, and surrounding or inclosing an opening or space, and being provided with a conduit, channel, or passage-way. 70
- In testimony whereof I have signed my name to this specification in the presence of two subscribing witnesses. 75
